UNITED STATES PATENT OFFICE.

WILLIAM S. BURRIS, OF RICHARDSON, TEXAS, ASSIGNOR OF ONE-HALF TO JAMES E. HARRIS,
OF RICHARDSON, TEXAS.

COMBINATION-TOOL.

No. 890,258.

Specification of Letters Patent.

Patented June 9, 1908.

Application filed August 17, 1907. Serial No. 389,019.

To all whom it may concern:

Be it known that I, WILLIAM S. BURRIS, a citizen of the United States, residing at Richardson, in the county of Dallas and State of Texas, have invented a new and useful Combination-Tool, of which the following is a specification.

This invention relates to combination tools of that general class especially designed for use by track walkers in alining and repairing rail-way tracks and has for its object to provide a comparatively simple and inexpensive device of this character embodying in its structure a claw bar, wrench and maul.

A still further object of the invention is to generally improve this class of devices so as to increase their utility, durability and efficiency as well as to reduce the cost of manufacture.

Further objects and advantages will appear in the following description, it being understood that various changes in form, proportions and minor details of construction may be resorted to within the scope of the appended claims.

In the accompanying drawings forming a part of this specification: Figure 1 is a perspective view of a combination tool constructed in accordance with my invention. Fig. 2 is a side elevation of the same.

Similar numerals of reference indicate corresponding parts in all of the figures of the drawings.

The improved device forming the subject matter of the present invention is principally designed for use by track walkers in repairing and alining rail way rails and includes a body portion consisting of a longitudinally disposed bar 5 having one end thereof flattened at 6 and provided with a terminal socket 7 constituting a wrench.

That portion of the bar opposite the socket 7 is bent at an angle to the longitudinal axis of the bar and deflected laterally at 8, said deflected portion being provided with a V shaped recess 10 which forms a claw so that the tool may be used for removing spikes and similar fastening devices from rail way ties.

The rear face of the bar 5 at the deflected end thereof is provided with a thickened portion or enlargement 11 which forms a fulcrum for the claw so that the spikes or other fastening devices may be removed from the cross ties with very little exertion on the part

Extending transversely of the bar 5 at a point adjacent the claw 10 is an enlargement 12 preferably cast integral with the bar 5 and constituting a maul. The opposite ends of the enlargement or maul 10 are inclined or tapered to form oppositely disposed faces 13 and 14 for driving spikes and similar fastening devices in the cross ties, as shown. The end 14 of the maul is preferably smaller than the opposite end 13 thus permitting the reduced end of said maul to be used as a tampering device for packing ballast between the cross ties or for other purposes.

Attention is here called to the fact that the central portion of the maul on one side of the bar 5 projects a short distance beyond the enlargement or fulcrum 11 so that when the tool is used for extracting spikes the curved surface 15 of the maul by engagement with the cross tie or other supporting surface will form an additional fulcrum for the claw and thus materially assist in extracting the spikes from the cross ties.

The wrench head 7 is preferably provided with a reduced shank 16 which engages a correspondingly threaded recess in the adjacent end of the maul handle or bar 5, said wrench head being locked against rotation on the bar by means of a clamping screw or similar fastening device 17. By making the wrench head detachable the latter may be readily removed so as to permit the employment of larger or smaller heads, according to the nature of the work to be performed.

From the foregoing description it will be seen that there is provided an extremely simple, inexpensive and efficient device admirably adapted for the attainment of the ends in view.

Having thus described the invention what is claimed is:

A tool of the class described comprising a cylindrical bar having one end thereof flattened to produce a shank of angular cross sectional formation, said shank being bent at an angle to the longitudinal plane of the bar and thence deflected laterally and provided with a V shaped recess constituting a claw, the metal at the angle of deflection being thickened and spread laterally to form a fulcrum, and an enlargement formed integral with and extending transversely of the bar at the bent end thereof and having its central portion provided with a circumferential bearing face disposed in longitudinal alinement

2
with and forming in effect a continuation of the cylindrical portion of the bar, said enlargement extending an equal distance on opposite sides of the cylindrical bar to form a maul and having its side walls between the circumferential bearing face and the adjacent ends of the maul inclined to produce driving heads of different sizes, the bearing face of the enlargement on the fulcrum side of the bar being projected beyond the thickened portion of the claw for contact with the

ground, the opposite longitudinal edges of the shank between the claw and maul being converged on like angles in the direction of said maul.

15

In testimony that I claim the foregoing as my own, I have hereto affixed my signature in the presence of two witnesses.

WILLIAM S. BURRIS.
